UNITED STATES PATENT OFFICE.

JUSTUS B. ENTZ, OF CLEVELAND, OHIO, ASSIGNOR TO THE WHITE COMPANY, OF CLEVELAND, OHIO, A CORPORATION OF OHIO.

STARTER AND IGNITION CONTROL.

1,084,931.

Specification of Letters Patent.

Patented Jan. 20, 1914.

Application filed January 18, 1913. Serial No. 742,760.

To all whom it may concern:

Be it known that I, JUSTUS B. ENTZ, a citizen of the United States, residing at Cleveland, in the county of Cuyahoga and

5 State of Ohio, have invented a certain new and useful Improvement in Starter and Ignition Control, of which the following is a full, clear, and exact description.

This invention relates to starter and ignition controlling mechanism for internal combustion engines and has particular utility in connection with the starting and lighting systems of motor vehicles employing dynamo electric machines for starting 10 and lighting or battery charging purposes.

In one of its aspects the invention comprises an arrangement of starter and ignition controlling switching mechanism, or combination of starter and ignition switches 20 such that there is eliminated the possibility of premature ignition in a cylinder by the manipulation of the ignition switch while the engine is being turned over by the starter, and so that there will likewise be 25 precluded the possibility of stopping the engine by the ignition switch without disconnecting the battery and dynamo motor.

Another novel feature of my invention resides in the controlling switch for a dynamo 30 motor of the type having series and shunt field windings, which assist each other and provide a strong field and good starting torque when the dynamo electric machine is serving as a motor to turn over the engine, 35 and which have an opposing and voltage regulating action when the machine is serving as a generator. In this aspect, my invention includes a starter switch which connects and disconnects the battery and armature 40 of the dynamo motor, and also connects and disconnects the shunt field winding, the shunt field winding being disconnected (on the opening of the starter switch), not later than and preferably before the armature 45 and battery are disconnected, so as to preclude the possibility of the armature and battery being disconnected without also the disconnecting of the shunt field winding from both the armature and battery.

50 My invention may be briefly summarized as consisting in certain novel combinations and arrangements of parts which will be described in the specification and set forth in the appended claims.

55 My invention is of utility as far as the ig-

nition part of the system is concerned when either a magneto or a battery is used as a source of igniting current, and in the drawings, Figure 1 is a diagrammatic view of a starting, lighting and ignition system embodying my invention and employing a magneto as the source of ignition current; and Fig. 2 is a similar view wherein the battery is used as a source of ignition current.

Referring now to the drawing, it will be 60 seen that the starter and lighting system includes a dynamo electric machine 10, having an armature 10^a, a main shunt field winding 10^b, and an auxiliary series field winding 10^c. The armature is preferably coupled or 65 geared to the engine by a single power transmission agency which with suitable speed reduction at all times connects the dynamo electric machine to the engine and is in service when the dynamo electric machine is 70 serving both as a motor and as a generator. I have not deemed it necessary to show this power transmitting means, but it is believed to be sufficient to state that a simple chain and sprocket drive between the dynamo electric machine and pump shaft will suffice. If desired, of course, the dynamo electric machine might be coupled directly to the 75 crank shaft. When the dynamo electric machine is serving as a motor, it receives current from the storage battery 11, and at such time, the two field windings 10^b, 10^c assist each other so as to produce maximum field strength and provide large torque for starting purposes. When the dynamo electric 80 machine is driven as a generator, the direction of current through the series field winding reverses, and the latter then serves as a back series winding, so that the field produced by the current in the series winding 85 opposes that produced by the current in the shunt field winding, and as the opposing action varies with the speed and consequently with the value of the current in the series winding, the dynamo electric machine serves 90 as a substantially constant potential generator, and the battery is charged at a substantially constant ampere rate.

The lamps of the lighting circuit are 95 shown at 12. These lamps are connected by suitable conductors 13 to the conductors 14, connecting the battery and dynamo electric machine.

In Fig. 1, the source of ignition current 100 is a magneto 15, only a conventional show-

ing of which is made. The magneto may, of course, be of any suitable construction, such as a high tension magneto whose primary may be short circuited, as hereinafter explained, to cut the magneto into and out of service, and whose secondary is connected in the usual manner to a distributor 16 having contacts connected to the several spark plugs of a multiple cylinder engine. 5 The primary circuit is adapted to be closed and opened in the usual manner by a make and break device or interrupter 15^a. For the control of the dynamo motor and for the ignition control, I employ two mechanically connected switches including a starter switch 17 and an ignition switch 18 whose switch blades are mechanically connected together so that the two switches together constitute in effect unitary switching mechanism. 10 The starter controlling switch 17 serves to connect and disconnect the battery and dynamo electric machine and also to connect and disconnect the shunt field winding of the dynamo electric machine, and the ignition switch is utilized, in this case, to cut in or out the ignition by short circuiting the magneto or opening the short circuit. One terminal of the series winding 10^c is connected to the blade of switch 17, which 15 is adapted to engage two separate contacts or points 17^a and 17^b, the former of which is connected to one terminal of the shunt winding 10^b, and the latter of which is connected to one terminal of the armature 10^a. In accordance with one part of my present invention, the contact 17^a is made shorter than the contact 17^b so that when the starter switch is opened, the circuit of the shunt field winding is opened prior to the opening 20 of the circuit between the battery and the armature. By breaking the circuit of the shunt field winding prior to the time that the battery and dynamo electric machine are disconnected, there is precluded the possibility of the armature and battery being disconnected without also the disconnecting of the shunt field winding from both the armature and battery. Consequently, there is 25 eliminated the liability of the battery discharging through the shunt field winding, as might occur if the shunt field winding were not disconnected from the battery, when the armature-battery circuit is opened, and there is also eliminated the liability of the voltage 30 of the dynamo electric machine building up to a dangerous point, as might occur if the machine were run on open circuit with the shunt field winding connected across the terminals of the machine. The two switches 35 17 and 18 are so arranged and interconnected that when the starter switch is closed, the ignition switch is opened so that the magneto is enabled to supply ignition current to the engine, and when the ignition switch is closed, to cut out the magneto, the

starter switch must be opened. I prefer to employ a switch with progressive positions, which include the position marked *a—a* in Fig. 1 of the drawings, wherein the starter switch is closed, and the ignition switch is opened, the position marked *b—b* wherein the starter switch is full open and the ignition switch is closed, and the position marked *c—c* which is an intermediate position with both switches open. 70

The advantages of the above described arrangement include the following: It is impossible for premature ignition to be caused in the cylinder by the manipulation of the ignition switch while the engine is being turned over by the starter. There is no liability of the operator stopping the engine by closing the ignition switch without also opening the starter switch so as to disconnect the battery and dynamo electric machine, as well as the shunt field winding from both the battery and armature of the dynamo electric machine. The intermediate position *c—c* enables the dynamo electric machine to be cut out of service without affecting the operation of the engine, *i. e.*, without stopping the engine. Furthermore, the apparatus has the previously mentioned advantages resulting from the fact that the shunt field winding is disconnected on the opening of the switch, not later than the opening of the battery and armature circuit. 85

In Fig. 2 I have shown a slight modification, as far as the ignition part of the system is concerned, but wherein the same advantages described in connection with Fig. 1 are attained. In this instance, the dynamo electric machine and the battery connections are the same in all respects as those shown in Fig. 1. However, instead of employing a magneto for ignition purposes, the storage battery 11 is used as a source of ignition current. A primary ignition circuit 20 includes the primary of an induction coil 21 having a secondary connected to the distributor. The primary circuit includes a suitable make and break device 22, a cam operated circuit breaker being here shown. For the control of the starter and ignition, I employ a pair of interconnected switches here designated 23 and 24. The switch 23 is connected to the battery and dynamo electric machine terminals precisely in the same manner as shown in Fig. 1. The switch 24, however, is included directly in the primary ignition circuit 20. The blades of these two switches are so connected together and arranged with respect to the switch contacts that when the starter switch is closed, the ignition switch is likewise closed, for starting and normal engine operation, the switches then being in the position marked *d—d*. When the starter switch is full open, the ignition switch is open, the switches then being in the position marked *c—c*. When the switches are 90

in intermediate position *f*—*f*, however, the 5 starter switch is open, but the ignition switch is still closed, thus allowing the engine to be operated with the starting and lighting apparatus cut out of service. It will be understood without further description that all the advantages enumerated in the description of the apparatus disclosed in Fig. 1 are attained also in the apparatus 10 shown in Fig. 2.

Having thus described my invention, what I claim is:

1. In combination with an internal combustion engine, a dynamo electric machine 15 adapted to start the engine and adapted to be driven thereby when the engine is started, a storage battery, an ignition circuit for the engine, and unitary starter and ignition controlling switch mechanism having progressive positions including respectively a position wherein the dynamo electric machine and battery are connected into circuit, and the ignition circuit is operative, a position wherein the dynamo electric machine and 25 ignition circuit are both cut out of service, and a third position wherein the dynamo electric machine is cut out of service at said switching mechanism, and wherein the ignition circuit is operative.
2. In combination with an internal combustion engine, a dynamo electric machine adapted to start the engine and to be driven thereby when the engine is started, a starter switch for connecting and disconnecting the dynamo electric machine and battery, an ignition circuit, an ignition switch, said starter switch being connected to the ignition switch in a manner such that when the starter switch is closed, the battery 35 and dynamo electric machine are connected into circuit, and the ignition switch is in position to render the ignition circuit operative, when the starter switch is full open, the ignition switch renders the ignition circuit 45 inoperative, and the dynamo electric machine and battery are disconnected at said switch, and when the starter switch is in an intermediate open position, the ignition switch renders the ignition circuit operative, 50 and the dynamo electric machine and battery are disconnected at said starter switch.
3. In combination with an internal combustion engine, a dynamo electric machine for engine starting and lighting or battery 55 charging purposes, a storage battery, said dynamo electric machine including an armature, a shunt field winding, and a series field winding adapted to produce fields which assist each other while the dynamo electric 60 machine is serving as a motor, and oppose each other when the dynamo electric machine is serving as a generator, and a starter switch for connecting and disconnecting the battery and armature of the dynamo electric 65 machine, and for connecting and disconnect-

ing the shunt field winding, said switch disconnecting the shunt field winding prior to disconnecting the battery and armature.

4. In combination with an internal combustion engine, a dynamo electric machine 70 for engine starting and lighting or battery charging purposes, said dynamo electric machine having an armature, a shunt field winding and a series field winding adapted to produce fields which assist each other when the dynamo electric machine is serving as a motor, and which oppose each other when the dynamo electric machine is serving as a generator, a storage 75 battery, an ignition circuit, and unitary switching mechanism for connecting and disconnecting the battery, armature and shunt field winding of the dynamo electric machine and for controlling the ignition circuit, said switching mechanism disconnecting the shunt field winding from the battery and armature prior to disconnecting the battery and armature.

5. In combination with an internal combustion engine, a dynamo electric machine 80 for engine starting and lighting or battery charging purposes, said dynamo electric machine having an armature, a shunt field winding and a series field winding adapted to produce fields which assist each other 85 when the dynamo electric machine is serving as a motor and which oppose each other when the dynamo electric machine is serving as a generator, a storage battery, an ignition circuit, and unitary switching mechanism for connecting and disconnecting the battery, armature and shunt field winding of the dynamo electric machine and for controlling the ignition circuit, said switching 90 mechanism having progressive positions including respectively a position wherein the dynamo electric machine and battery are connected into circuit and the ignition circuit is operative, a second position wherein the dynamo electric machine is cut out of 95 service, and the ignition circuit is operative, and a third position wherein the dynamo electric machine and ignition circuit are both 100 cut out of service.

6. In combination with an internal combustion engine, a dynamo electric machine 105 for engine starting and lighting or battery charging purposes, said dynamo electric machine having an armature, a shunt field winding and a series field winding adapted to produce fields which assist each other when the dynamo electric machine is serving as a motor, and which oppose each other when the dynamo electric machine is serving as a generator, a storage battery, an ignition 110 circuit, and unitary switching mechanism for connecting and disconnecting the battery, armature and shunt field winding of the dynamo electric machine and for controlling the ignition circuit, said switching 115 mechanism disconnecting the shunt field winding from the battery and armature prior to disconnecting the battery and armature.

mechanism disconnecting the shunt field winding from the battery and armature prior to disconnecting the battery and armature, and said switching mechanism having progressive positions including respectively a position wherein the dynamo electric machine and battery are connected into circuit and the ignition circuit is operative, a second position wherein the dynamo electric machine is cut out of service and the

ignition circuit is operative, and a third position wherein the dynamo electric machine and ignition circuit are both cut out of service.

In testimony whereof, I hereunto affix my signature in the presence of two witnesses.
